FILLING CARRIER DRIVE FOR SHUTTLELESS LOOMS

Maurice R. Flamand, Valley Falls, R.I., and Anthony J. Tosches, Milford, Mass., assignors to Draper Corporation, Hopedale, Mass., a corporation of Maine

Application April 9, 1956, Serial No. 577,004

3 Claims. (Cl. 139—122)

This invention relates to an improvement in shuttleless looms and more particularly, to improved means for actuating the filling inserting members.

It is a general object of the invention to devise means for reciprocating filling inserters which shall be simple and inexpensive to manufacture and which shall function with a high degree of efficiency.

A more specific object is that of devising such means which shall employ only spur type gearing.

A further object is that of providing reciprocating means actuated through cranks or eccentrics and pitman means and in which the particular motion delivered shall conform to the most acceptable practice insofar as the efficiency of the filling insertion is concerned.

Another object is that of keeping lost motion in the system at a minimum.

Another object is that of devising mechanism in which noise, wear and need for adjustments are all kept at a minimum.

Other objects will be apparent from the following more detailed disclosure.

In shuttleless looms filling is sometimes inserted by flexible means adapted to be attached to reciprocating wheels or the like. These flexible members are equipped with means by which picks of filling may be drawn from a supply at the side of the loom and inserted first as a loop pushed part way through the shed and which is then taken by the opposite inserting means and a released end of the loop drawn through to the opposite side, all as shown and described in United States Patent 2,641,285.

For the most part these flexible inserters are attached to light, wheel-like means which are oscillated to and fro, the inserters being wrapped about the wheel and then released from it as they are projected into the fabric. These wheels have been oscillated by various types of sector driven gearing, by combinations of oscillating bevel geared trains, and by oscillating levers which were cam operated. All are complicated, use cams, gear systems and devices which introduce high friction loads and in many instances do not eventually produce a proper or nearly theoretically correct motion for the inserters. Again some are expensive and complicated, and also wear rapidly. They frequently have too much lost motion so that improper action is often experienced.

According to the invention, a very simple system has been devised which employs spur type gears only and which is operated by eccentrics or cranks on a rotating shaft in the loom. These cranks are connected to crossheads movable in slides by pitman members while the crossheads are provided with rack teeth to mesh either with a gear connected to the same shaft the wheel is mounted upon, or, more preferably, as will be explained, with an intermediate gear which will reverse the rotation of the wheel from what would prevail if driven more directly.

The invention will be described in greater detail by reference to a specific embodiment thereof as shown in the accompanying figures of drawing, wherein:

2

Fig. 1 is a front elevation of a loom to which the invention has been applied.

Fig. 2 is a sectional view showing one end of the loom, the parts being enlarged as compared to Fig. 1.

Fig. 3 is a section taken along a vertical plane as at line 3—3, Fig. 2.

Fig. 4 is a section taken at line 4—4, Fig. 3.

Fig. 5 is a detail view of a small part of the drive showing a modification.

Fig. 6 is a diagrammatic view showing the timing as in the preferred form.

Now referring to Fig. 1, a loom similar to that of United States Patent 2,641,285 comprises among other parts, loomsides 10 and 11, girt 12, a breast beam 13 and a shaft 14 which is driven by a suitable source of power such as the motor 15 through gears (not shown). This shaft may also carry cams and other parts which form a part of the loom operating mechanism, but should, however, be driven one revolution for each pick inserted. The loom has harness frames 16, a top motion 17 and a fabric take-up and wind-up means such as shown in United States Patent 2,722,240, by which a fabric roll 18 is eventually formed.

As shown more clearly in Figs. 2 and 3 in addition to Fig. 1, a combination of bracket 19 bolted to loomside 10 and a brace 20 support a housing 21 and its cover 22 within which a wheel 23 is mounted by certain means which permits adjustment, to a shaft 24. This wheel is of light construction and has attached at an appropriate point

30 at its periphery, a flexible inserting member in the form of a steel tape 25 which has a filling engaging head 26 of the type shown in United States Patent 2,705,508. This tape tends to assume a straightened condition and is aligned to enter the shed by a guide 27. It is to be understood that the mechanisms at either end of the loom are substantially similar, but that one inserter has a head adapted to project a loop of filling part way through the shed while the other is provided with a hooked head to draw an end across the remainder of the shed.

40 Bracket 19 is also formed with a web 28 supporting a bearing 29 for one end of shaft 24, and then extends rearwardly to form a housing 30 closed by a cover 31 within which is enclosed a gear 32 fixed to that end of shaft 24 as shown in Fig. 4. A second bearing 33 is provided for shaft 24 which is adjustably restrained axially by a collar 34 at the bearing 29 and a ball 35 at the shaft end, this ball being positioned by a screw 36 locked in cover 31 by a nut 37.

45 The wheel 23 is oscillated through a prescribed angle by means including a crosshead 38 at one face of which teeth are cut to form a rack 39. This crosshead is movable in a slide 40 made up from guides 41 and 42 bolted to a faced end 43 of the extended part 44 of housing 30. The cover 31 is also projected to enclose this extended casing 44 and forms a support 45 for a bearing 46 aligned with another bearing 47 in the extension 44 within which is rotatable a short shaft 48 of an intermediate gear 49. This gear conveys motion from the rack to gear 32 but reverses the direction from what it would otherwise be for reasons to be explained.

50 The crosshead is reciprocated by an eccentric means carried by some driven member of the loom, the speed of which should be equal to one revolution for each complete pick to be inserted. Here this means takes the form of a crank 50 having a flange 51 in which there are cast three or more bosses 52 drilled for screws or bolts to pass through the flange and also into another disk or, as here shown, gear 53. The hub 54 of the crank is thus free to be moved about shaft 14 since either the bolt holes in the flange or in the disk are elongated. The parts may be adjusted and are locked in an adjusted position by screws 55 and 56 threaded through a part of the flange

51 and bearing against pin 57 which is fixed in the disk or gear as the case may be. The position of screws 55 and 56 is maintained by lock nuts 58 and 59.

Crank 50 is connected to the crosshead by a pitman 60 pivoted at 61 at the crank end and at 62 at the crosshead. The latter is an extending part of the plate or back of the crosshead which is preferably bolted or otherwise fixed to that part which carries the rack teeth and slides in the guideways formed by parts 41, 42 and 43. A positioning dowel may be used. It is preferred that each pivot be provided with an anti-friction bearing. The pitman head at one end (here the top end) is split as shown to facilitate removal.

The wheel 23 is also adjustable to an extent since as it is bolted to a flange 63 through slots or the like, its position may be adjusted and locked by eccentric disks 64 and 65 held in place by two of the screws and bearing against a pin 66 in the hub of the wheel.

The rotation of the shaft 14 thus reciprocates the crossheads and their racks through the pitman connections and the racks, in turn, oscillate the gears 32 through the intermediate gears 49 so that wheels 23 likewise oscillate to actuate the filling inserters. The use of these intermediate gears is very important since it favorably affects the timing of the parts. The inserting of filling must be timed in looms of this type to occur while the lay is substantially stationary.

There is a dwell of about 200° more or less during which the filling carriers or inserters may be in the shed. This means that for the remainder of the cycle both should be outside the shed and, of course, that time interval occurs while the carriers are being withdrawn beyond the shed extremities so that it becomes desirable to slow down the movement of the carriers during that part of the cycle. Otherwise, the alternative, if a simple drive through an eccentric or crank is to be had, is to widen the loom by extending the distance of centers 24 beyond the shed extremities.

As seen in Fig. 6, the crank 50 is at lower part of its swing during that interval and due to the peculiarities of a crank and short pitman, the actual distance x which the rack is moved is very small compared to the distance it would move if the top of the swing were being used then as it would be if there were no intermediate gear. In the latter case the same period of dwell would be accompanied by a carrier movement of y . In actual practice the difference in a 40-inch loom is about 7 inches or a total added loom width of 14 inches with dwell of the lay coinciding with the top part of the crank swing. The present arrangement also makes possible the easier engagement of the filling by the inserting head and assures a slower motion at the start while the carrier is drawing a loop from the supply at the very high rate of pull off from that supply as is characteristic of these looms.

At Fig. 5, a simple form of the drive without an intermediate gear is shown but, of course, this, although simple, does have the disadvantages above mentioned. Here a gear 67 is directly in mesh with a rack 68 reciprocated by a pitman 69 similar to the previously described structure, but, of course, with functions occurring at opposite extremities of crank throw as compared to the preferred form. The wheel 70 will be oscillated,

and if width of loom is not of concern and higher speeds not so important, this simpler arrangement may be employed.

The problems of lubrication and gear wear are reduced since there are fewer gears, fewer bearings and the gearing is all of the spur type presenting less friction. The bearings carry smaller loads and practically no thrust load. Thus costs are down, both for the original installation and for upkeep.

These desirable characteristics are obtained without the use of cams which are expensive, costly and also give rise to high friction loads at parts of the cycle.

While one embodiment of the invention has been disclosed, it is to be understood that the inventive concept may be carried out in a number of ways. This invention is, therefore, not to be limited to the precise details described, but is intended to embrace all variations and modifications thereof falling within the spirit of the invention and the scope of the claims.

We claim:

1. In a loom having opposed flexible filling inserting members, wheels to which said flexible members are attached and by which they are alternately advanced and retracted, a driven shaft in said loom and means for oscillating said wheels in unison which comprises at each wheel, a spur type gear fixed for rotation with said wheel, a crosshead and slide disposed adjacent said gear, an intermediate spur type gear rotatably mounted to mesh with the gear first mentioned, and teeth on said crosshead constituting a rack meshing with the teeth of said intermediate gear, an eccentric means fixed to the shaft end and a pitman connecting said crosshead and eccentric means.

2. In a loom having opposed flexible filling inserting members, wheels to which said flexible members are attached and by which they are alternately advanced and retracted, a driven shaft in said loom, means for oscillating said wheels in unison which comprises at each wheel, a shaft to which that wheel is fixed and a spur type gear fixed to the shaft adjacent the wheel, a crosshead and slide means positioned for movement adjacent said gear, a crank fixed to the shaft end and a pitman pivoted at the crank and to said crosshead, rack teeth on said crosshead and an intermediate, motion reversing spur type gear meshing with said rack teeth and with the teeth of the gear first mentioned.

3. Mechanism as defined in claim 2 wherein said crank is angularly adjustable to time the action of the filling inserting means.
